SHEAR SHARPENER

Edgar G. Gereau, Sioux City, Iowa

Application July 23, 1940, Serial No. 347,031

1 Claim. (Cl. 76—82.2)

This invention is a device to facilitate the sharpening of shears, and an object of the invention is to provide a device of this character particularly designed for use by barbers in sharpening hair cutting scissors or shears.

In accordance with the present invention means is provided whereby the shears may be conveniently held with the blade thereof to be sharpened in a position tending to facilitate the sharpening thereof, and to enable the user to obtain an edge for the blade of the shear that is most conducive to the efficient cutting action of the shear.

The invention, together with its objects and advantages will be best understood from a study of the following description taken in connection with the accompanying drawing, wherein—

Figure 1 is a plan view of the device illustrating the manner in which the same is employed for holding the blade of a shear for the purpose of sharpening the blade,

Figure 2 is a detail sectional view taken substantially on the line 2—2 of Figure 1,

Figure 3 is an end elevational view of the device,

Figure 4 is a detail sectional view taken substantially on the line 4—4 of Figure 1,

Figure 5 is a perspective view of the movable clamping jaw.

Referring more in detail to the drawing, it will be seen that in the preferred embodiment thereof the device consists of a flat oblong board 5 of any suitable dimensions, and the same is equipped at one end thereof with a clamp indicated generally by the reference numeral 6.

The clamp 6 in accordance with the present invention consists of an attaching plate 7 which is disposed flatly against the under side of the board 5 adjacent one end thereof and is secured to the board 5 through the medium of screws or other fastening elements 8.

The plate 7 has one edge thereof turned upwardly to provide a jaw body 9 from which extends upwardly, and at an angle to the perpendicular, a stationary narrow elongated jaw 10.

Complementing the jaw body 9 is a movable jaw body 11 that has formed integral therewith and disposed at an angle thereto a jaw 12 that complements the jaw 10 and is movable toward and away from the jaw 10 for coacting clamping action therewith.

The jaw 12 is normally yieldably urged away from the jaw 10 through the medium of a coil spring 13. The spring 13 has an end portion thereof seated in a socket 14 provided in an end

edge of the board 5, and a second end portion bearing against the jaw body 11 as shown; the jaw body 9 being provided with an opening 15 aligning with the socket 14 and through which the spring 13 extends to engage the jaw body 11, as clearly shown in Figure 2.

The jaw member 12 is guided in its movements toward and away from the jaw 10 by a pair of bolts 15 that extend through aligned openings provided therefor in the jaw bodies 9 and 11 as shown in Figure 4 and are equipped with thumb nuts 16, which when threaded home on the bolts 15 serve to cause the jaw member 12 to move into clamping association with the jaw 10 whereby a blade of the shears may be readily clamped between the jaws 10 and 12 to be held thereby in position during the sharpening of the edge of the blade of the shear.

In Figure 1 a pair of shears is shown fragmentarily and in dotted lines and is indicated generally by the reference numeral 17.

In using the device the nuts 16 are threaded toward the outer ends of the bolts 15 to permit the jaw 12 under action of the spring 13 to move to a position away from the jaw 10, thus permitting the selected blade of the shears 17 to be positioned between the jaws 10 and 12. When this has been done, the nuts 16 are threaded home on the bolts 15 causing the jaw 12 to move towards the jaw 10 and in this manner the blade of the shears 17 is positively clamped between the jaws 10 and 12 to be held thereby during the employment of a file or other suitable instrument for effecting a sharpening of the cutting edge of the clamped blade.

The board 5, as is apparent, serves as a convenient support for the clamp 6 and facilitates the handling of the device.

It is also to be observed that the jaws 10 and 12 are disposed at such an angle to the perpendicular as to serve to hold the blade of the shears at that angle to the perpendicular found most effective in obtaining a bevel for the cutting edge of the shears regarded as most conducive for efficient cutting action of the shears.

It is thought that a clear understanding of the construction, assembly, manner of use and advantages of the device embodying the features of the present invention will be had without a more detailed description thereof.

It is also to be understood that while I have herein shown and described the preferred embodiment of the invention, it is no wise intended to restrict the invention to the precise details of construction combination and arrangement of

elements as described, other than as required by the prior art and scope of the appended claim.

Having thus described the invention, what is claimed as new is:

In a device of the character described, a clamp for holding the blade of a pair of shears to facilitate the sharpening thereof, said clamp comprising an elongated base having a socket in one end portion, a jaw body having an attaching plate secured to the bottom side of said base at the socketed end portion thereof, said jaw body further having openings therein one of said openings being in alignment with the socket in said base, an angularly disposed jaw extending from said jaw body, bolts extending through the other of said jaw body openings, a movable jaw

body having openings therein mounted on said bolts with the bolts extending through the openings in said movable jaw body, nuts on the end portions of said bolts for moving said movable jaw body toward said first named jaw body when said nuts are fed home on the bolts, a jaw on said movable jaw body opposed to said first named jaw, and a compression spring having one end portion engaged in said socket and extending through the aligned opening in said first named jaw body with its other end portion impinged against said movable jaw body to normally urge said movable jaw body away from said first named jaw body and open said jaws when said nuts are fed outwardly on said bolts.
